W. R. GILLIES

HEAT INSULATING TAPE

Filed Sept. 22. 1922

Inventor
W.R. Gillies
William Readby
McCalloch Prince Atty's

UNITED STATES PATENT OFFICE.

WILLIAM R. GILLIES, OF CHICAGO, ILLINOIS, ASSIGNOR TO UNION ASBESTOS & RUBBER COMPANY, OF CHICAGO, ILLINOIS, A CORPORATION OF ILLINOIS.

HEAT INSULATING TAPE.

Application filed September 22, 1922. Serial No. 589,787.

To all whom it may concern:

Be it known that I, WILLIAM R. GILLIES, a citizen of the United States, and resident of Chicago, in the county of Cook and State 5 of Illinois, have invented certain new and useful Improvements in Heat Insulating Tape, of which the following is a full, clear, concise, and exact description, reference being had to the accompanying drawings, 10 forming a part of this specification.

My invention relates to a tape which is formed of a heat insulating material, and which is adapted to be applied to fluid conducting pipes of various kinds. When the 15 pipes to be insulated convey high temperature steam or hot water, the heat insulating material employed is preferably fire resisting, or, at least, capable of withstanding extremely high temperatures without disinte- 20 gration. The hereinafter mentioned forms of asbestos have proved excellent materials for my purpose.

My invention contemplates the provision 25 of an improved tape which affords the requisite insulation, which, if necessary, is capable of withstanding high temperatures, and which easily may be applied tightly and smoothly to the pipe in connection with which it is employed, the tape being so con- 30 structed as to compensate for the unequal stresses to which the margins of the tape are subjected during the process of its applica- 35 tion to the pipe.

In the accompanying drawing illustrating 35 my invention,

Figure 1 illustrates the manner of applying my improved insulating tape to a pipe;

Figure 2 is a transverse sectional view of the tape, and

Figure 3 is a transverse section illustrating the elements of the tape as they appear prior to the closing of the fabric tube or sheath.

In the drawing, reference letter A generally indicates the insulating tape of my invention, B indicates a pipe to which the tape is applied, and C indicates devices for securing the tape upon the pipe.

The tape A consists of a flattened tube or 50 sheath 1, which is preferably formed of a heat insulating and heat resisting material, such as a textile fabric, the woof and warp of which are in the form of cords of asbestos fibre. Disposed side by side within the tube 55 or sheath 1, and extending continuously and

longitudinally therethrough, is a multiplicity of independent ropes 2-2, each of which is formed of asbestos fibre. Each of the ropes 2-2 may consist merely of twisted asbestos fibres, or may consist of a number of asbestos cords twisted together to form a rope. 60

In the manufacture of the tape of my invention, the sheath 1 is initially in the form of a long, flat strip of asbestos fabric, as is best illustrated in Figure 3. The ropes 2-2 are positioned upon and longitudinally of the sheath-strip, as shown in the last mentioned figure, and then the edges 1^a-1^a of the strip are turned over the ropes and overlapped, as indicated in Figure 2. The overlapped portions of the sheath are then permanently secured together by any suitable heat resisting cement, such as silicate of soda. 70

In applying the tape to a pipe, that end 75 of the tape which is first applied is preferably beveled a distance equal to approximately three times the diameter of the pipe. One wrap is then made around the pipe with the beveled end of the tape lying in a transverse plane of the pipe. The said end of the tape is then secured by means of a hose clamp or band of the type shown at C. The tape is then tightly and closely spiraled around the pipe the distance required. Additional clamps or bands C are preferably placed at intervals of from twelve to eighteen inches and assure a very neat and secure application of the insulating tape. 85

I have previously alluded to the fact that 90 the flattened tube or sheath 1 contains a multiplicity of asbestos ropes 2-2. While in the manufactured product, the ropes 2-2 lie very closely together and, so far as the matter of heat insulation is concerned, constitute a single body of asbestos felt, they 95 retain their individuality to the extent that they yield to different degrees under the tensions to which the tape is subjected during the course of its application to the piping, 100 and thus compensate for the unequal tensions to which the different margins of the tape are subjected during the spiraling operation. This construction enables the tape to fit the pipe very tightly and snugly, with 105 exceptionally tight fits between the lateral margins of adjacent turns of the tape.

Having thus illustrated and described my invention, what I claim is new is:

An insulating tape adapted to be tightly 110

spiralled about a pipe comprising a flexible sheath consisting of a flattened tube formed of a textile fabric of asbestos and a multiplicity of independent asbestos fibre ropes disposed side by side and longitudinally of said sheath and substantially filling the latter.

In witness whereof, I hereunto subscribe my name this 19th day of September, 1922.

WILLIAM R. GILLIES.
